(57) **CLAIM**

The ornamental design for an electric vehicle charging system, as shown and described.

DESCRIPTION

FIG. 1 is an upper left front perspective view of an electric vehicle charging system showing our new design;

FIG. 2 is an upper right rear perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof;

FIG. 8 is a bottom plan view thereof;

FIG. 9 is a top left front perspective cutaway view showing illumination elements;

FIG. 10 is a side and enlarged elevational cutaway view of the electric vehicle charging system of FIGS. 4 and 6; and, FIG. 11 is an enlarged bottom plan view showing details of air vents of the electric vehicle charging system of FIG. 8. The shade lines in the Figures show contour and not surface ornamentation.

The broken lines in the Figures show portions of the electric vehicle charging system which forms no part of the claimed design.
